United States Patent Office

Des. 197,989
Patented Apr. 14, 1964

197,989

BOX

Leo R. Slaton, Chicago, Ill., assignor to Swiss Harmony,
Inc., Chicago, Ill., a corporation of Illinois

Filed June 28, 1963, Ser. No. 75,568

Term of patent 7 years

(Cl. D58—12.6)

FIG. 1 is a perspective view of a box embodying my new design, and

FIG. 2 is an end elevational view thereof.

The rear not shown is substantially the same as the front shown, the end not shown is a mirror image of the end shown and the bottom is plain.

I claim:

The ornamental design for a box, substantially as shown and described.
